Primary Examiner — Jeffrey D Asch(74) *Attorney, Agent, or Firm* — Morgan, Lewis & Bockius LLP(57) **CLAIM**

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a rear perspective view thereof.

The broken lines that are immediately adjacent to claimed surfaces and define unshaded regions, represent the bounds of the claimed design. The broken lines that are shown within the broken line boundaries are directed to environment. The broken lines and the non-shaded regions within the broken lines form no part of the claimed design.
